UNITED STATES PATENT OFFICE.

BYRON PHELPS, OF SEATTLE, WASHINGTON, ASSIGNOR OF ONE-HALF TO
THEODORE NELSON, OF CHICAGO, ILLINOIS.

LOCK.

SPECIFICATION forming part of Letters Patent No. 626,340, dated June 6, 1899.

Application filed March 10, 1897. Renewed November 30, 1898. Serial No. 698,371. (No model.)

To all whom it may concern:

Be it known that I, BYRON PHELPS, a citizen of the United States, residing at Seattle, in the county of King and State of Washington, have invented a certain new and useful 5 Lock, of which the following is a specification.

My invention relates to locks; and my object is to provide a lock which may be inserted in a notch in the stile of a door.

10 In the embodiment of my invention shown in the drawings, Figure 1 represents a side view of my lock, parts thereof being in section on the line W X of Fig. 2. Fig. 2 represents a plan view of Fig. 1 on the line Y Z. 15 Fig. 3 represents a back view, showing parts broken away and other parts in section, of the lock represented in Figs. 1 and 2. Fig. 4 represents a detail of one side plate. Fig. 5 represents a stile of a door, having a notch into 20 which my lock is adapted to be inserted. Fig. 6 represents a rear view of a modification of my device. Fig. 7 shows a side elevation, and Fig. 8 a front elevation, of my lock in position as applied to the stile of the door. Figs. 25 9, 10, and 11 show details.

In the construction shown in the drawings I have provided a main frame to support the mechanism. This main frame has a side C³ and preferably an opposite side C⁵, in this 30 embodiment formed by two portions 24 24, with suitable connections joining the sides. The main frame also embraces two hollow spindle-bearings d d', extending transversely outside of the same and preferably formed 35 integral therewith. These spindle-bearings are separated from each other—that is, there is a space between the same through which certain parts of the lock may project, such as, in this embodiment, the roll-back.

40 C' is an escutcheon-plate surrounding the bearing d' and may be integral with that side of the frame; but I do not limit myself to a construction in which the escutcheon-plate is integral with the frame or with the bearing, because it is obvious that many changes may be 45 made in the construction herein disclosed without departing from the spirit of my invention. In the present embodiment this plate is applied directly to and is integral with 50 the side C³ and helps form one side of the frame carrying the bearing d'.

22 is a connection between the spindle-bearing d and one side of the frame. The frame preferably has a face-plate C² projecting laterally from one side thereof, in this 55 embodiment extending clear across the front end of the frame and having an opening therein for the latch-bolt, as shown. This face-plate is preferably formed by the front end of the frame itself being integral with the 60 frame; but it may obviously consist of a plate separate from the frame, if desired.

65 C is a second side plate, having a hole therein by means of which it may be slipped over the spindle-bearing d. This side plate has a 65 projection 20, having lips 21 to embrace the face-plate C², and these two side plates C and C' may be adjusted relatively to each other by the screws 3 3 to fit doors of different thicknesses, all as clearly shown in Figs. 7 and 8. 70

The latch mechanism embraces a latch bolt or head I, pivoted between lugs k by the pins i. The latch-bolt projects through the opening in the face-plate C².

75 H² is a shoe formed in this embodiment of a slide H and yoke H'. This slide H is pivotally attached to the bolt I by the pins i', and has a slot h² therein having an enlarged aperture h³. The yoke H' has a T-shaped head h', which may be inserted through the 80 aperture h³ and slipped down to the position shown in Figs. 1 and 2, where it will be held from disengagement by reason of the slot h³ being narrower than the head h'. The yoke H' has preferably two legs, as shown, each 85 one of which has a projection h. The ends of springs 1 and 2, coiled around pin l, press on H and H', respectively, to throw them, and so the bolt I, forward.

90 The spindle-bearings d and d' are separated and between them is a sleeve G, carrying bolt-actuating means, consisting in this embodiment of a double roll-back g' g, which contacts with projections h h on shoe H². From the sleeve G project outwardly spindles E E', in 95 this embodiment connected together, as shown in Fig. 9. These projections on either side of the sleeve G may each be denominated a "spindle," as by the rotation of either of them the latch-bolt may be withdrawn, as 100 hereinafter explained. These spindles are preferably chambered, as shown, and in the

shaft formed by said two spindles are three slots, as shown in Fig. 9. In one of said extensions or spindles E' is a longitudinal slot e, as shown in Figs. 2, 3, and 9, and a second longitudinal slot 12. Within this chambered spindle E' extends locking means to lock the opposite spindle E, and in this embodiment also spindle E', from rotation, consisting of a lock-rod M, having a projection 6 passing through slot e, and a second projection 7 passing through slot 12. The position of the slots with relation to the other parts is shown in Fig. 3 by dotted lines.

13 is a slot in the sleeve G, and 9 is a slot in the frame, which slots register when the sleeve and roll-back are in their normal position of rest. The projection 7 passes through the slot in the sleeve G, as shown in Fig. 3, but on account of the longitudinal slot 12 may be moved out of this slot 13 in the sleeve, thus disconnecting the sleeve and roll-back from the spindle into slot 9, which will lock the spindle E, and in this embodiment spindle E' also, from rotation. This longitudinal movement of pin 7 may be accomplished by a finger-piece K extending transversely outside the spindle and carrying cam-faces formed by the sides of the inclined slot K' therein, in which slot the projection 6 moves. By the rotation of the finger-piece K the projection 6, and consequently the lock-rod M and projection 7, will be moved longitudinally of the spindle. 10 is a sleeve covering the cam and pin to conceal the same, and F is a knob having a shank f, which abuts against the slotted sleeved part of finger-piece K and holds it between itself and bearing d, as shown clearly in Fig. 3.

11 is a transverse slot in spindle E, through which projects a pin 8 on a key-rod L, within said spindle, and said projection 8 also passes through and fits a hole in sleeve G, as shown in Fig. 3.

E² is a longitudinal hole in the end of spindle E, through which a key is adapted to be inserted to engage the end of key-rod L to rotate the same. It will be obvious that when the finger-piece K has been rotated so as to bring the projection 7 into the slot 9 and lock the spindle E from rotation a key may be inserted in a hole E² and the key-rod L rotated within the fixed spindle. The sleeve G and roll-back g will thus be moved as pin 8 fits the hole in said sleeve, and the latch will be thrown back without disturbing the locked spindle E.

P is a strike-plate having the usual aperture therein, over which is a hood 30. This strike-plate preferably has a projection or wing 31, standing substantially perpendicular to the face of said plate, as shown in Figs. 1 and 2. The side plate C' is preferably set back on the frame, as shown in Fig. 2, so that this wing 31 will project along the side of the frame to aid in forming the jamb of the door when the door is closed, as shown. The hood

and wing 31 prevent tampering with the bolt from outside the door.

It will be seen that by my construction I provide an extremely simple lock which may be completely assembled for shipment and yet may be applied in position in the stile of the door without disassembling any of the parts. It is applicable to either a right-hand or left-hand door by merely reversing its position and may be inserted in a notch in the stile of a door and securely clamped therein by drawing the side plates toward each other. The latch is always movable whether either spindle is locked or not, and the construction of the lock and hooded strike-plate prevents unlawful tampering with the latch-bolt. The face-plate C' allows for different adjustments of the side plates relatively to each other, and consequently one lock may be applicable to several thicknesses of doors, and yet the notch in the door will be entirely covered and no slot will be left, although the same lock is applied to stiles of differing thickness. This dispenses with the necessity of a different lock for each thickness of stile. A latch-bolt having a breadth nearly as great as the thickness of the stile of the door can be used, as nearly the whole distance between the side plates can be utilized, which is a distinct advantage over the usual style of locks. Considering the construction as shown in Fig. 3 the right-hand spindle might be on the inside of a door and the left-hand spindle upon the outside. By mere rotation of finger-piece K the door will be securely locked from entrance from the outside; but by the insertion of a proper key into said spindle the latch may be thrown back without interfering with the locked spindle.

In Fig. 6 I show a modification of my device in which each spindle has a rod corresponding to the rod M and also a finger-piece, so that by the rotation of either finger-piece the opposite spindle will be fixed, and consequently the door cannot be opened by the rotation of said opposite spindle. This modification is particularly applicable for doors between connecting rooms.

It is obvious that many modifications of my device may be made without departing from the spirit of my invention.

What I claim is—

1. In a lock, a main frame to support the latch mechanism and adapted to be inserted in a notch in the stile of a door, having a plurality of separated and hollow spindle-bearings attached thereto and extending transversely outside of the same, said frame having an opening at one end for a latch-bolt.

2. In a lock in combination, a main frame to support the latch mechanism and adapted to be inserted in a notch in the stile of a door, having a plurality of separated and hollow spindle-bearings attached thereto and extending transversely outside of the same, and plates extending transversely of said bearings

and adjustable with relation to each other so as to clasp the sides of said stile.

3. In a lock in combination, a main frame to support the latch mechanism and adapted to be inserted in a notch in the stile of a door, having a plurality of separated and hollow spindle-bearings attached thereto and extending transversely outside of the same, a face-plate extending transversely from one side of said frame, and side plates extending transversely of said bearings and adjustable with relation to each other so as to clasp the sides of said stile, one of said plates embracing said face-plate.

15 4. In combination in a lock a main frame, a side plate integral therewith, spindle-bearings also integral with said frame and extending laterally therefrom, and a face-plate extending laterally from the plane of one side 20 plate across the edge of the other side plate, said other side plate being adjustable with relation to said face-plate whereby the notch in the door-stile will be kept closed.

5. In a lock in combination latch mechanism embracing a latch bolt or head, a plurality 25 of rotatable spindles, bolt-actuating means connected with one of said spindles and adapted to be operated to retract said bolt by the rotation of said spindle in either direction, 30 and mechanism to lock said spindle against rotation and operative from the side of said lock opposite said locked spindle.

6. In a lock in combination, latch mechanism embracing a latch bolt or head, a plurality 35 of rotatable spindles, bolt-actuating means adapted to be operated thereby to move said bolt, mechanism to lock one of said spindles against rotation, and a movable finger-piece 40 projecting outside of the other of said spindles transversely of the axis thereof and connected with said locking mechanism to operate the same.

7. In a lock in combination, latch mechanism embracing a latch bolt or head, a plurality 45 of normally-connected rotatable spindles, bolt-actuating means adapted to be operated thereby to move said bolt, mechanism to lock one of said spindles against rotation, and a movable finger-piece projecting outside 50 of the other of said spindles transversely of the axis thereof and connected with said locking mechanism to operate the same.

8. In a lock in combination, latch mechanism, a plurality of rotatable spindles extending to said mechanism to operate the same, one of said spindles being chambered, locking means extending therein and adapted to hold the other of said spindles against rotation, and a device adapted to be operated by the 55 fingers extending outside of said chambered spindle transversely of the axis thereof and connected with said locking means to operate the same, and means, connected with said latch mechanism and adapted to operate the 60 same independently of said locked spindle, operative from the same side of said lock as said locked spindle.

9. In a lock in combination, latch mechanism, a plurality of rotatable spindles extending to said mechanism to operate the same and normally connected so as to operate together, one of said spindles being chambered, locking means extending therein and adapted to hold the other of said spindles against rotation and a device adapted to be operated by the fingers 70 extending outside of said chambered spindle transversely of the axis thereof, and connected with said locking means to operate the same, and means, connected with said latch mechanism and adapted to operate the 75 same independently of said locked spindle, operative from the same side of said lock as said locked spindle.

10. In combination, latch mechanism, a plurality of rotatable spindles extending thereto, 80 one of said spindles being chambered, a roll-back normally connected with one of said spindles and rotatable therewith to operate said latch mechanism, and means in said chambered spindle to disconnect said roll-back from one of said spindles and lock said 85 spindle to a stationary part.

11. In combination, latch mechanism, a plurality of rotatable spindles extending thereto, 90 one of said spindles being chambered, a roll-back normally connected with the other of said spindles and rotatable therewith to operate said latch mechanism, and means in said chambered spindle to release said roll-back from the other of said spindles and lock 95 said other spindle to a stationary part.

12. In a lock in combination, latch mechanism, a plurality of spindles extending thereto to operate the same, one of said spindles being chambered, means to lock one of said 100 spindles, a connection from said means passing into said chambered spindle and a device extending outside of said chambered spindle and joined to said connection to operate the same, and means, connected with said latch 105 mechanism and adapted to operate the same independently of said locked spindle, operative from the same side of said lock as said locked spindle.

13. In a lock in combination, a frame, a 110 spindle-bearing in said frame, a spindle therein, a relatively rotatable sleeve and a hollowed knob on said spindle having a projection from the inside of said knob to hold said sleeve against a portion of said bearing.

14. In a lock in combination latch mechanism, a knob-spindle to actuate the same carrying a hollowed knob, movable means connected with said latch mechanism located within said spindle and having an extension laterally through the same, a rotatable finger-piece carried outside of said spindle between said knob and latch mechanism having an outward projection into said hollowed knob, said projection carrying a cam-face adapted to contact with and move said extension.

15. In combination in a lock, a chambered spindle, latch mechanism, locking means in said spindle to hold it against rotation, and a

device movable on the exterior of said spindle and connected with said locking means to operate the same.

16. In a device of the character described a strike - plate having a latch - bolt aperture therein, a hood over and covering said aperture to protect the latch-bolt, and a wing projecting outwardly from the face of said plate at one side of said aperture and substantially perpendicular to the face of said plate to aid in forming the jamb.

17. An escutcheon-plate comprising a main portion having a spindle-hole therein and a broadened projection extending laterally of said main portion at one side thereof and substantially in the same plane therewith and located substantially opposite said spindle-hole, said projection having a lug extending therefrom in substantially the same plane therewith, in combination with a lock-frame having a face-plate, said face-plate having a lateral extension across the edge of said escutcheon-plate, the relative position of said face-plate and escutcheon-plate being determined by said lug, said face-plate and escutcheon-plate being adjustable relatively to each other.

18. In a lock in combination a main frame, a side plate on each side of said frame and a face-plate extending laterally from one side of the frame across the edge of the opposite side plate, said side plate and face-plate being adjustable relatively to each other.

19. In combination in a lock side plates and a face-plate extending laterally from the plane of one side plate across the edge of the other side plate, said other side plate being adjustable with relation to said face-plate whereby the notch in the door-stile will be kept closed.

20. In a lock in combination, latch mechanism embracing a latch bolt or head, a plurality of rotatable spindles, bolt-actuating means connected with one of said spindles and adapted to be operated to retract said bolt by the rotation of said spindle in either direction, and mechanism embracing a detent movable longitudinally of said spindle to lock said spindle against rotation and operative from the side of said lock opposite said locked spindle.

21. In a lock in combination, latch mechanism embracing a latch bolt or head, a plurality of rotatable spindles, bolt-actuating means adapted to be operated thereby to move said bolt, mechanism to lock one of said spindles against rotation embracing a detent movable longitudinally of said spindle, and a movable finger-piece projecting outside of the other of said spindles transversely of the axis thereof and connected with said locking mechanism to operate the same.

22. In a lock in combination, latch mechanism embracing a latch bolt or head, a plurality of rotatable spindles, bolt-actuating means adapted to be operated thereby to move said bolt, mechanism to lock one of said spindles against rotation, and a movable finger-piece projecting outside of the other of said spindles transversely of the axis thereof and connected with said spindle with said locking mechanism to operate the same.

dles transversely of the axis thereof and connected laterally through said spindle with said locking mechanism to operate the same. 70

23. In a lock in combination, latch mechanism embracing a latch bolt or head, a plurality of normally - connected rotatable spindles, bolt-actuating means adapted to be operated thereby to move said bolt, mechanism embracing a detent movable longitudinally of said spindles to lock one of said spindles against rotation and a movable finger-piece projecting outside of the other of said spindles transversely of the axis thereof and connected with said locking mechanism to operate the same. 75

24. In a lock in combination, latch mechanism embracing a latch bolt or head, a plurality of normally - connected rotatable spindles, bolt-actuating means adapted to be operated thereby to move said bolt, mechanism to lock one of said spindles against rotation and a movable finger-piece projecting outside of the other of said spindles transversely of the axis thereof and connected laterally through said spindle with said locking mechanism to operate the same. 80

25. In a lock in combination, latch mechanism, a plurality of rotatable spindles extending to said mechanism to operate the same one of said spindles being chambered, locking means, extending therein and adapted to hold the other of said spindles against rotation, embracing a detent movable longitudinally of said spindles, and a device adapted to be operated by the fingers extending outside of said chambered spindles transversely of the axis thereof and connected with said locking means to operate the same. 95 100

26. In a lock in combination, latch mechanism, a plurality of rotatable spindles extending to said mechanism to operate the same one of said spindles being chambered, locking means extending therein and adapted to hold the other of said spindles against rotation, and a device adapted to be operated by the fingers extending through said chambered spindle transversely of the axis thereof and connected with said locking means to operate the same. 110 115

27. In a lock in combination, latch mechanism, a plurality of rotatable spindles extending to said mechanism to operate the same and normally connected so as to operate together, one of said spindles being chambered, locking means extending therein and adapted to hold the other of said spindles against rotation, said locking means embracing a detent movable longitudinally of said spindles, and a device adapted to be operated by the fingers extending outside of said chambered spindle transversely of the axis thereof and connected with said locking means to operate the same. 120 125

28. In a lock in combination, latch mechanism, a plurality of rotatable spindles extending to said mechanism to operate the same and normally connected so as to operate to- 130

gether, one of said spindles being chambered, locking means extending therein and adapted to hold the other of said spindles against rotation, and a device adapted to be operated by the fingers extending through said chambered spindle transversely of the axis thereof and connected with said locking means to operate the same.

29. In a lock in combination, latch mechanism, a plurality of spindles extending thereto to operate the same one of said spindles being chambered, means to lock one of said spindles embracing a detent movable longitudinally of said spindles, a connection from said means passing into said chambered spindle, and a device extending outside of said chambered spindle and joined to said connection to operate the same.

30. In a lock in combination, latch mechanism, a plurality of spindles extending thereto to operate the same one of said spindles being chambered, means to lock one of said spindles, a connection from said means passing into said chambered spindle, and a device extending laterally through said chambered spindle and joined to said connection to operate the same.

31. In a lock in combination, latch mechanism embracing a latch bolt or head, a plurality of rotatable spindles, bolt-actuating means connected with one of said spindles and adapted to be operated to retract said bolt by the rotation of said spindle in either direction, mechanism to lock said spindle against rotation and operative from the side of said lock opposite said locked spindle, and means, connected with said latch mechanism and

adapted to operate the same independently of said locked spindle, operative from the same side of said lock as said locked spindle. 50

32. In a lock in combination, latch mechanism embracing a latch bolt or head, a plurality of rotatable spindles, bolt-actuating means adapted to be operated thereby to move said bolt, mechanism to lock one of said spindles against rotation, and a movable finger-piece projecting outside of the other of said spindles transversely of the axis thereof and connected with said locking mechanism to operate the same, and means, connected with said latch mechanism and adapted to operate the same independently of said locked spindle, operative from the same side of said lock as said locked spindle. 50

33. In a lock in combination, latch mechanism embracing a latch bolt or head, a plurality of normally-connected rotatable spindles, bolt-actuating means adapted to be operated thereby to move said bolt, mechanism to lock one of said spindles against rotation, and a movable finger-piece projecting outside of the other of said spindles transversely of the axis thereof and connected with said locking mechanism to operate the same, and means, connected with said latch mechanism and adapted to operate the same independently of said locked spindle, operative from the same side of said lock as said locked spindle. 55

In testimony whereof I affix my signature in presence of two witnesses.
